Toulmin & Toulmin
ATTORNEY

UNITED STATES PATENT OFFICE

RAE E. COCHRAN, OF COLUMBUS, OHIO, ASSIGNOR TO THE D. L. AULD COMPANY, OF COLUMBUS, OHIO, A CORPORATION OF OHIO

HUB CAP

Application filed June 13, 1929. Serial No. 370,557.

This invention relates to improvements in hub caps, and has for its object the production of a hub cap easily inserted in the hub and securely held thereto when so inserted, 5 but may be removed without great difficulty.

It is particularly the object of this invention to provide a hub cap in which, in both inserting and removing the cap from the hub, the line of force, tending to flex the spring 10 holding means, lies in the axis of the spring itself, enabling the use of light springs.

It is also an object of this invention to provide a hub cap composed essentially of a body member having attached thereto spring 15 means for engaging a coacting part of the hub for the purpose of holding the cap in place.

These and other advantages will appear from the description, taken in connection 20 with the drawings.

Referring to the drawings:

Figure 1 is a bottom plan view of the cap, showing the locking springs attached thereto.

Figure 2 is a sectional view of the cap.

The body of the cap, which is designated by the numeral 1, is composed of a sheet of metal, for instance sheet metal, circular in shape, turned over and in on its edges to 20 form a bead 2 and a hub engaging flange 3. The body is somewhat dish-shaped and has extending substantially at right angles thereto the flange 3.

In the flange there are spaced slots 4. In 35 the drawings there are shown three of these slots arranged at equal distances from each other. Attached to the body member and adjacent the slots are spring tongue members 5. These tongues are radially arranged and fastened to the body member by means of rivets 6. However, other means might be used 40 for fastening the tongues to the body member.

On the outer ends of the tongues there are 45 formed snap members, designated by the numerals 7, 8 and 9. The snap members are made by bending the tongue or spring members 5 at a right angle and forming thereon snap parts 7, which extend through the slots. On the outer ends of the snap parts there are

formed gradually inclined portions 8. These parts 8 are the parts which engage the coacting locking means on the hub when the cap is being inserted in position. After the cap has been inserted in position the coacting 55 engaging means on the hub engages an abrupt inclined part 9 of the snap members.

The snap members are so constructed that whenever the cap is being inserted into or removed from the hub the line of force tending to flex the spring lies on the axis of the spring itself; that is, in the longitudinal direction of the spring, thereby making it unnecessary that the springs or tongues be large and heavy as would otherwise be required. 60 It will be observed from Figure 2 that the part of the snap member adjacent the flange rests in the bottom of the slots and is held in position therein.

Extending over the body member and of 70 the same general shape is an ornamental plate 10. This ornamental plate has its outer periphery bent over to form a bead 11 in engagement with the bead 2 of the body member so that the ornamental plate is firmly and 75 securely held on the body member by means of the bead 11 engaging the bead 2. The surface of the ornamental plate may be of any design and shape, and of any suitable color. This ornamental plate has in the center thereof a hole 12, back of which hole is 80 a design plate 13. The edges of the design plate fit between the ornamental plate and the body member and is securely held in 85 position thereby. The design plate may have any suitable design thereon.

From the foregoing description it will be seen that there has been provided a hub cap composed essentially of one member having attached thereto spring locking means for 90 the purpose of holding the cap in engagement with the hub. Any form of ornamental or design plate may be used to suit the convenience and taste and the likes of the user or manufacturer.

I desire to comprehend within my invention such modifications as may be clearly embraced within my claims and the scope of my invention.

Having thus fully described my invention, 100

what I claim is new and desire to secure by Letters Patent, is:

1. In a hub cap, a body member, means on said body member for engaging a hub, an ornamental plate for said body member, said ornamental plate having a hole therein, and a design plate behind said hole and supported by said body member and said ornamental plate.
- 10 2. In a hub cap, a body member having an inwardly directed hub engaging flange forming with the body member a circumferential bead, an ornamental plate for said body member having its edges turned over in engagement with said bead, said ornamental plate having a hole therein, and a design plate back of said hole and supported by said body member and said ornamental plate.
- 15 3. In a hub cap, a body member turned over and in to form a circumferential bead and a hub engaging flange, means attached to said body member and extending through said flange to lock the cap to the hub, an ornamental plate for said body member having its edges turned over in engagement with said bead, said ornamental plate having a hole therein, and a design plate back of said hole and supported by said body member and said ornamental plate.
- 20 30 In testimony whereof, I affix my signature.
RAE E. COCHRAN.
